DRESS ENSEMBLE

Miriam Abrams, New York, N. Y., assignor to Barnet Ginsburg & Nat Abelson, Inc., New York, N. Y., a corporation of New York

Application November 10, 1949, Serial No. 5,966

Term of patent 3½ years

(Cl. D3—26)

To all whom it may concern:

Be it known that I, Miriam Abrams, a citizen of the United States, resident of the city of New York, in the county of New York, in the State of New York, have invented a new, original, and ornamental Design for a Dress Ensemble, of which the following is a specification, reference being had to the accompanying drawing, forming part thereof.

In the drawing,

I claim:

The ornamental design for a dress ensemble, substantially as shown.

MIRIAM ABRAMS.
